UNITED STATES PATENT OFFICE

156,238

DESIGN FOR A BEDSPREAD OR THE LIKE

Karl Christian Hoffmann, Rutherford, N. J., assignor to Simmons Company, New York, N. Y., a corporation of Delaware

Application July 24, 1948, Serial No. 147,751

Term of patent 14 years

(Cl. D92—2)

To all whom it may concern:

Be it known that I, Karl Christian Hoffmann, a citizen of the United States, residing at Rutherford, in the county of Bergen and State of New Jersey, have invented a new, original, and ornamental Design for a Bedspread or the like, of which the following is a specification, reference being had to the accompanying drawing, forming part thereof.

The figure is a plan view of a quarter section of a bedspread or the like, showing my new design. The other sections are identical with that here disclosed, and are arranged in proper relation to complete the bedspread or the like.

I claim:

The ornamental design for a bedspread or the like, substantially as shown and described.

KARL CHRISTIAN HOFFMANN.
